CLAIM

The ornamental design for a music bottle, as shown.

DESCRIPTION

FIG. 1 is a front perspective view of a music bottle showing my new design in a closed position;

FIG. 2 is a front view thereof; the back, left side and right side view are the same as the front view;

FIG. 3 is a top view thereof;

FIG. 4 is a bottom view thereof; and,

FIG. 5 is a front perspective view of the music bottle shown in an open position with the lid removed and showing the music playing feature of the music bottle inside the lid thereof.
